James A. Karns, Akron, Ohio, assignor to Fawick-Grip Company, Akron, Ohio, a corporation of Ohio

Filed July 5, 1962, Ser. No. 70,809

Term of patent 14 years

(Cl. D34—5)

FIGURE 1 is a side view of a golf club grip showing my new design;

FIGURE 2 is an enlarged view of the upper end thereof;

FIGURE 3 is a vertical section on the line 3—3 thereof; and

FIGURE 4 is a horizontal section on the line 4—4 thereof.

The characteristic feature of my design resides in the combination on the golf club grip disclosed, of specific patterning of transverse and vertical grooved clusters which progressively diminish in size from the wider closed end to the narrower open end substantially as shown.

The broken line showing of a shaft and club head in FIGURE 1 is for illustrative purposes only.

I claim:

The ornamental design for a golf club grip, as shown and described.
